UNITED STATES PATENT OFFICE.

WOLF ARBETTER, OF CHELSEA, MASSACHUSETTS, ASSIGNOR TO ARBETTER FELLING MACHINE COMPANY, OF BOSTON, MASSACHUSETTS, A CORPORATION OF MAINE.

SEWING-MACHINE.

1,035,939.

Specification of Letters Patent. Patented Aug. 20, 1912.

Application filed May 27, 1907. Serial No. 375,847.

To all whom it may concern:

Be it known that I, WOLF ARBETTER, a citizen of the United States, residing in Chelsea, county of Suffolk, and State of Massachusetts, have invented an Improvement in Sewing-Machines, of which the following description, in connection with the accompanying drawing, is a specification, like letters on the drawing representing like parts.

This invention relating to sewing machines for blind stitching has for one of its objects to provide this class of sewing machine with means for plaiting or gathering a part 15 of one fabric on a part of another fabric at suitable intervals where desired, during the stitching of one part of a fabric to another part.

My invention is especially desirable for 20 uniting a sleeve-lining or sleeve to the inner lining of a coat at or about the arm-scye, or a sleeve to an arm-scye in the making of a garment in which it is desired that the stitches do not show in the body material 25 of the garment.

My invention also includes mechanism whereby the stitch-forming mechanism in 30 making the blind stitches may be so adjusted as to cause the needle to make either of its movements in a straight line parallel to the line of feed, or all its movements diagonal to the line of feed and at any desired degree of angularity, or its movements alternately straight parallel to the line of 35 feed and diagonal to the line of feed at any desired degree of angularity.

My invention also involves a mechanism for replacing the fabric after it has been 40 pushed upwardly by what is known as the bender to present the fabric in the path of the needle.

I have illustrated my invention as embodied with a blind stitch sewing machine of the type represented in United States 45 Patent No. 830,699, granted to me September 11, 1906, many of the parts in the machine herein to be described being shown in said patent in connection with other parts added thereto to enable a sleeve or sleeve 50 lining to be plaited or gathered into a garment, the plaiting or gathering being at intervals in order that the end of a sleeve may be properly attached to an arm-scye of the garment.

Figure 1 is a front end view; Fig. 1^a is 55 a detail of the roller carrier and eccentric; Fig. 2 is a rear or side view of the parts shown in Fig. 1; Fig. 3 is a detail showing part of the plaiting means and replacer; Fig. 4 is an enlarged detail showing the apparatus employed for plaiting or gathering one part or portion of a fabric, as a sleeve, on to another portion of a fabric constituting part of a garment; Fig. 5 is a like view showing the plaiting or gathering means inoperative; Fig. 6 is a top or plan view of Fig. 4; Fig. 7 is a top or plan view of Fig. 5; Fig. 8 is a side view of Fig. 6 looking from the right; Fig. 9 shows part of the work to be done on the machine to be herein 70 described; Fig. 10 is a detail showing the replacer.

The sewing machine bed A, the overhanging arm A', the head casing A², A^{2x}, the main shaft A³, the connection B², the needle-carrying rock-shaft B⁷, the needle-carrying arm b², the needle a², the take-up D, the shaft A⁷ for driving the loop-taker a, the needle bearing carrier or shaft B¹⁰ having at its lower end an enlargement B^{10x} 80 with which is connected by a screw 10 a bearing to sustain the needle-rock-shaft, the arm c^{6x} connected with said shaft B¹⁰ and provided with an adjusting device c⁶, the stop c⁷, the spring c⁸ surrounding shaft B¹⁰, the rod d³ having attached to its lower end d^{3x} by a screw 10 the shank d⁸ of the presser-foot d⁹ having a rearward extension d¹⁰, said presser-foot having a space 48, the space closer d¹⁶, the spring-sustained throat-plate E', the feeding device E², the shaft D¹⁴ having a cam D¹⁵ for moving the feeding device, the fulcrum E⁷ for the lower end of the feed device, the bender G are and may be all substantially as shown in said 95 patent with but slight alterations, to be hereinafter described.

The arm c^{6x} connected with the shaft B¹⁰ by set screw 20 may be so adjusted with relation to said shaft that when said arm contacts with the stop c⁷ under the action of the spring c⁸, the needle shaft will occupy a position substantially at right angles to the line in which the work is moved by the feeding device E² to make what is called its 100 straight thrust; that is, the thrust which is substantially parallel with the direction of the length of the seam and with the infolded

edge, and to facilitate this adjustment the arm c^{6x} is provided with an adjusting device c^6 so as to insure just the proper position for the needle in its thrust into the body material f' resting on the work-support. The upper end of the shaft B^{10} has connected therewith by a bolt 8 a link or arm 7 having at its outer end an ear 70, said ear having a stud 63 see Fig. 1, that receives over it a hole 5, see Fig. 1^a, of a roller-carrying arm 4 provided at its upper end with a stud 3 on which is mounted a roller 2. The arm 4 has an elongated slot 12 that receives an eccentric 13 forming part of a roller-adjusting device 15. The adjusting device and eccentric have a hole that receives the threaded shank of a bolt 18, the threaded end of said bolt, see Fig. 1, entering the screw-threaded hole in the lug referred to. The edge of the adjusting device has a series of numbers, and the lug of the arm 7 has a pointer 17 coacting with said numbers. The main shaft has upon it near its outer end a gear C' that engages a larger gear C both common to said patent, the gear C being rotated once to two rotations of the gear C'. The gear C has a face cam C^x and the roller 2 referred to may be acted upon by the face of said cam, the latter when operating on the roller 2 turning said rock-shaft in one direction preparatory to making one stitch, the spring C³ turning said shaft in the opposite direction preparatory to making the next or succeeding stitch. By turning the eccentric 13 referred to, the position of the roller on the arm 7 may be so changed as to cause the cam acting at each rotation on said roller, to turn the shaft B^{10} and needle shaft bearing B^9 more or less, to thus provide for different positions of the needle when making its angular thrust, or its thrust at an angle to the direction of the length of the seam, as when entering the superimposed material f at an angle to its edge. When the roller 2 is so positioned on the arm 7 that the cam exerts its full throw on the roller, the greater the angularity of the thrust of the needle, and when the roller 2 is so adjusted on the arm 7 that the cam in its rotation will not strike said roller, then the rocking or swinging movement of the rock-shaft B^{10} may be entirely suspended and each thrust of the needle will be a straight thrust, so it will be understood that by turning the adjusting device, the rocking movement of the shaft B^{10} may be entirely suspended, in which case each thrust of the needle will be what is called a straight thrust; and so also it will be understood that if each thrust of the needle is to be a diagonal thrust, then the adjusting device c^6 will be so turned with relation to the arm c^{6x} that said adjusting device in contact with the stop c^7 will hold the rock-shaft in any desired position, so that the thrust of the

needle will be a diagonal thrust and just alike for each thrust, and at this time the roller-carrying arm and roller will be so adjusted as to be entirely removed from contact with its cam C^x.

The gear C engages and at each full rotation thereof rotates gear H², and a cam or eccentric h carried thereby acts once during each rotation of the latter gear on the upper end of a device, see Figs. 3 and 3^a, 75 that I have chosen to designate as a replacer, it comprising a rod h' having a portion h² connected to its lower end adjustably by a screw h³ in a slot h⁴, so that the lower portion or acting extremity of the replacer may be adjusted vertically on or with relation to the rod h', said extremity being usually so adjusted that when the replacer completes its working strike it will occupy a position substantially in the plane of the 80 bottom of the presser-foot in the space 48. The upper end of the replacer has a collar h⁵ suitably pinned thereto, and between said collar and the part A^{2x} of the head-casing is interposed a spring h⁶ that acts normally to retain the upper end of the replacer 85 always in contact with the cam h. The replacer is guided in its vertical movements by a tubular bearing h⁷ held in the part A^{2x}, the spring h⁶ surrounding said bearing, the 90 latter having a notch 22, see Fig. 2, that is entered by a pin 23, the slot and pin insuring a straight line movement for the replacer. The bender G is the same as in my said patent, and it is actuated in like 100 manner to bend the material preferably at each alternate thrust, the bender being essential in bending the material when the needle enters the body material or when the needle is making its so-called straight thrust. 105 It will be understood that the bender as it rises meets the under side of the body material f resting on the throat-plate and bends the material upwardly into the space 48 of the presser-foot, and after a stitch is made 110 and the bender is retracted or lowered, the usual feeding device rises through the slots in the usual throat-plate 24 of the work-support, engages the under side of the material and feeds the same for a stitch. 115

I have found in practice, with some material and especially with material of more than one thickness, that the bender jams or crowds the material into the space 48 of the presser-foot, and when the machine is being 120 run at high speed, the bent material in said space interferes with the movement of the fabric by the feed, as if the movement of the fabric is held back due to the upwardly bent material yet in the presser-foot, of course 125 there must be a variation in the feed stroke, which is detrimental to good work. Consequently I have devised the replacer before referred to, and I have so timed its movements that it occupies its elevated po- 130

sition under the action of the spring h^a while the bender is being operated to bend the material into the space 48 of the presser-foot, and immediately as the bender is retracted, the replacer descends on the upwardly bent portion of the fabric and pushes the same backwardly out from the space 48, the lower end of the replacer entering the space 48 in the presser-foot and stopping when its end arrives substantially in the plane of the under side of the presser-foot, said replacer thus partially filling the space in the presser-foot during the time that the feed, engaging the under side of the material, is moving the material over the under side of the presser-foot, the work-support at such time being slightly relieved from its pressure, as provided for in said patent, in order not to interfere with or clamp the work during the feeding operation.

The cam C^x has an annular groove 24 so cut into a part of its periphery as to leave a cam 30 shaped as shown by dotted lines, Fig. 1, that contacts with one edge of an actuator 31 comprising essentially a bent arm shown detached in Fig. 3, said arm being pivoted at 32. A spring 33 connected with a stud 34 extended from said actuator and connected at its opposite end with a fixed stud 35 keeps the actuator in contact normally with said cam during its rotation. The lower end of the actuator has a connected extension 36 attached by screws 36^x, the extension being carried forwardly and slotted to embrace a stud 37 rising from a blade-carrier 38 mounted loosely upon the rear part d^{10} of the presser-foot d^a . The blade-carrier has a diagonal or inclined slot 39 that has coacting with it guiding means shown as two screws 40 located in said slot. The forward end of the blade-carrier 38 is shown as bent upwardly as at 41 to occupy an angular position, and has connected with it near its free end by suitable studs 42 a spring blade 43, said portion 41 being slotted as at 44, see Figs. 6 and 7, to receive a blade-controller 45 shown as a lever having an eccentric end and mounted on a pivot 46 thrust through the extension 41. When the controller 45 occupies the position Fig. 4, the spring blade occupies its operative position, but when turned backwardly into the dotted line position Fig. 5, the free end of the blade, due to its being made of spring metal, rises and occupies its inoperative position. When the controller is in the position full lines Fig. 4, the blade may be made to pucker or gather the fabric f' which is folded on itself, as shown in Figs. 6 and 7, said material being the upper end of a sleeve lining, of silk or other usual lining fabric, the same being laid on the lining support or shelf 50 herein represented as forming part of the presser-foot d^a , said shelf as constructed having an edge guide 52 and being slotted,

see Figs. 6 and 7, for the reception of screws 53. When the blade 43 occupies the position shown by dotted lines, Fig. 5, the controller also occupying its dotted line position, then the blade, in its forward movement, due to moving the carriage 38 in the direction of the arrow Fig. 4 by the actuator 31, will not strike the material f and consequently will not plait or gather the same. In the drawing f' is supposed to represent a portion of a garment to which the inturned end of a sleeve lining f is to be stitched about the usual arm-scye, or part of the body part of a coat or garment. In fact, the sleeve lining, when stitched into the coat may be stitched not only to the coat lining, but also to the inturned upper end of the sleeve part of the coat or the arm-scye of the coat at the portion thereof appearing in the back of the coat, or may be stitched only to the coat lining around the top of the shoulder from the shoulder-seam down to the under side of the arm-scye, where again the upper end of the sleeve lining may be attached not only to the lining of the coat, but also to the body material of the coat. The folded edge of the sleeve lining f may be made to abut the gage 52 sustained by the presser-foot. The extent of movement of the actuator and blade is controlled by a regulator 54 shown as a threaded screw having a long head notched as at 55 to be engaged by a locking device 56, the screw being projected more or less through a lug 57 carried by the actuator, to meet sooner or later the portion A^{2x} of the head casing of the machine.

The work-support E' is normally maintained in its elevated position by appliances fully described in said patent, said work-support being free to yield to the different thicknesses of material passing over the top of the work-support under the presser-foot.

It will be noticed that the needle-carrying rock-shaft B^7 differs somewhat from the rock-shaft designated by the same letter in said patent, in that the rock-shaft herein has at its outer end a rigidly connected arm a^{10} provided with a ball-shaped ring a^{12} fitted over a stud a^{13} carried by said arm, said ball-shaped roller being embraced by a bushing a^{14} concaved internally to fit the roller a^{12} and convexed externally to fit a concaved eye at the lower end of the connecting rod B^2 . The upper end of the connecting rod B^2 has a like bushing that embraces a like ball-like ring fitted over a stud a^{15} held in a stand a^{16} connected with the disk B common to said patent, by screws a^{17} , said disk being carried by the main shaft.

Prior to my invention devices for plaiting fabric have been provided with blades that meet the fabric and plait the same that it may be stitched to another fabric, and these blades have, so far as I am aware, been 130

5 moved in lines parallel to the direction in which the material is fed over the work-support, and these blades have plaited material that a straight needle might meet the 5 upper side of the material, pass straight through the same, and stitch the plaited material to another fabric, the path of movement of the needle being at right angles to the work-support, and in this class of 10 machinery the plaiting has been done preparatory to the formation of each stitch, or a plait has been formed for each thrust of the needle.

I believe that I am the first to combine 15 with blind-stitch-forming mechanism, any means whatever for plaiting a fabric; and also the first to combine with blind stitch-forming mechanism plaiting means wherein the operator may, at will, suspend the plaiting of one fabric being stitched to another fabric, this latter combination making it possible without stopping the stitch-forming mechanism to do work on a machine that has always heretofore been done by hand, 25 such for instance as sewing a sleeve lining into a coat at the arm-scye.

In plaiting devices heretofore used, the 30 blade or device acting on the material to plait the same has been moved during the plaiting operation only in the direction of the length of the seam. Herein the fabric to be plaited is acted upon by the plaiting device prior to the diagonal thrust of the needle, and I have so constructed the plaiting 35 means, as represented by the slots 39 and screws 40 that in addition to its longitudinal movement said plaiting means has imparted to it a slight transverse movement at an angle to the length of the seam and the 40 direction of feed, such movement of the plaiting means maintaining the folded edge of the material *f* being plaited, in a straighter line than is possible if the plaiting means had only a straight forward thrust. So 45 while I have illustrated my improvements as capable of being carried out by means herein represented and described, I desire to state that my invention is not limited to the particular shape shown for the plaiting 50 device or its actuating means, as I may employ any other usual or suitable means of the same or like nature.

I have herein shown means for rendering the blade of the plaiting device inoperative 55 by enabling the free end of the blade to rise so as not to contact with the material, and at the same time the device carrying the blade is moved continuously while the stitching is going on, but my invention would not 60 be departed from if the carrier for the blade should temporarily be thrown out of operation manually during the stitching operation, the blade at such time being inoperative to plait the fabric.

65 In my prior Patent No. 969,740, granted

September 6, 1910, I have described and claimed broadly means for maintaining the needle above the work-support in a plane diagonal to the line of feed, whereby only diagonal stitches may be formed at any desired angle, and in the machine of the said application and in my prior machines I have also provided for the operation of the needle in alternate planes first in the direction of the path of feed and then diagonal thereto with an adjustment to provide for any desired degree of angularity in the alternate thrust. The present invention involves as one feature means whereby the needle may be operated either (1) in a plane parallel to the direction of feed, or (2) in a plane of any desired degree of angularity so that all the stitches may be made diagonal to the line of feed at any desired angle, or (3) in planes alternately parallel to the line of feed and at any desired angle relative thereto so that the stitches may be made alternately, first, parallel to the line of feed and, second, at any desired angle with relation thereto.

Having described my invention, what I claim as new and desire to secure by Letters Patent is:—

1. In a sewing machine, a work-support, a needle and complemental stitch-forming mechanism located and operating above the work-support, means to actuate said needle and complemental stitch-forming mechanism to make a series of blind stitches, a plaiting device comprising a carrier and a blade, and manually controlled means for suspending the plaiting operation of the blade at will while the stitch-forming mechanism continues to operate.

2. In a sewing machine, work-supporting means, stitch-forming mechanism for forming blind stitches, plaiting means, and means to move the same both forwardly and laterally with relation to the length of the seam.

3. In a sewing machine, a work-support, a presser-foot, stitch-forming mechanism comprising a needle and looper located and operating above the presser-foot, means for actuating said needle to enter a folded edge of a layer of superimposed material to be stitched to material under the presser-foot, means for guiding the edge of the folded material, plaiting means to engage the material to be plaited, and means to move the plaiting means in the direction of movement of the material and diagonally with relation thereto prior to each thrust of the needle into the edge of said material.

4. In a sewing machine, a work-support, a presser-foot provided with an opening, means for projecting the material into said opening, stitch-forming mechanism located above the work-support, and means for operating it to cause the needle to pass over the

upper surface of the presser-foot and form blind stitches in the fabric projected therethrough, a guide to direct the edge of an upper layer of fabric adjacent said opening, 5 plaiting means, and means for operating it in the direction of movement of the material and diagonally thereto, whereby the upper layer of material is held up against said guide.

- 10 5. In a sewing machine, a work-support, a presser-foot provided with an opening, means for projecting the material into said opening, stitch-forming mechanism located above the work-support, and means for operating it to cause the needle to pass over the upper surface of the presser-foot and form blind stitches in the fabric projected therethrough, a guide to direct the edge of an upper layer of fabric adjacent said opening, 15 50
- 15 20 a plaiting device mounted on said presser-foot to slide back and forth thereon and diagonally with relation to the movement of the fabric, means for operating said plaiting device whereby the upper layer of fabric 25
- 20 25 while being plaited is held up against the said guide.

6. In a sewing machine, a work-support, a presser-foot having a bender space, means to change the size of said space, a bender to 30 press the material upwardly into the space of the presser-foot, and a replacer to act on the material pressed into said space by the bender to remove the same from said space.
- 35 7. In a sewing machine, a work-support, a bar having at its upper end an arm and at its lower end a bearing, a needle-carrier sustained in said bearing, a needle mounted in said needle-carrier, complemental stitch-forming mechanism, a cam and means for 40 operating the same, a link mounted on said arm and having a roller coöoperating with said cam, and an eccentric to adjust said link and consequently the extent of rocking

movement imparted to said bar from said cam.

8. In a sewing machine, a work-support, a bar having a bearing at its lower end, a needle-carrier sustained in said bearing, a needle mounted in said needle-carrier, complemental stitch-forming mechanism mounted and operative above the work-support, means for rocking said bar to cause the needle to move in a plane in the direction of feed and then in a plane diagonal thereto, 55 means for adjusting the operation of said rocking means to cause the bar either to remain stationary at any point of its range of oscillation or to oscillate through any desired angle in its range, whereby the 60 stitches may be made all parallel, all inclined at any desired angle, or all alternately parallel and inclined at any desired angle to the direction of feed.

9. In a sewing machine, a work-support, 65 stitch-forming mechanism mounted and operative above said work-support and comprising a needle entering and emerging on the same side of the fabric, whereby blind stitches are formed thereby, means for bodily oscillating the said needle to cause it to move on a plane in the direction of feed, and then in a plane diagonal thereto, means for adjusting the position and range of oscillation of said needle to cause its path of oscillation either to remain stationary at any desired point or to move through any desired angle, 70 whereby the stitches may be made all parallel, all inclined at any desired angle, or all alternately parallel and inclined at any 75 desired angle to the direction of feed.

In testimony whereof, I have signed my name to this specification in the presence of two subscribing witnesses.

WOLF ARBETTER.
